UNITED STATES PATENT OFFICE

THOMAS P. WRIGHT, OF ATLANTA, GEORGIA, ASSIGNOR TO MULTIWHEEL ROAD MACHINE COMPANY, INC., OF ATLANTA, GEORGIA, A CORPORATION OF GEORGIA

ROAD GRADER

Application filed January 18, 1932. Serial No. 587,413.

The invention relates to a road grader mainly designed for the cutting and grading of sand-clay and gravel surfaced roads and highways.

The primary object of the invention is the provision of a machine of this character wherein the same possesses considerable weight and is of considerable length, being supported upon six pairs of wheels, one pair of these being vertically adjustable so that when these wheels are lowered all the other wheels except the front pair are moved off the surface which enables the machine to be readily turned around and to cross bridges, tracks and the like with the scraper blade in inoperative position.

Another object of the invention is the provision of a machine of this character wherein the construction thereof is novel in form and is equipped with a laterally adjustable tongue which can be set at an angle, while the scraping blade is adjustable in a novel manner.

A further object of the invention is the provision of a machine of this character which is extremely simple in construction thoroughly reliable and efficient in its purpose, strong, durable, readily and easily adjusted, and inexpensive to manufacture.

With these and other objects in view, the invention consists in the features of construction, combination and arrangement of parts as will be hereinafter more fully described in detail, illustrated in the accompanying drawings, which disclose the preferred embodiment of the invention, and pointed out in the claims hereunto appended.

In the accompanying drawings:-

Figure 1 is a plan view of the invention.

Figure 2 is a side view thereof.

Figure 3 is a fragmentary sectional view on the line 3-3 of Figure 1 looking in the direction of the arrows.

Figure 4 is a detail sectional view showing how the front wheels are swiveled to the frame.

Figure 5 is a sectional view on the line 5-5 of Figure 1.

Figure 6 is a fragmentary vertical sectional view showing in detail the manner of adjusting the scraping blade.

Similar reference characters indicate corresponding parts throughout the several views in the drawings.

Referring to the drawings in detail, A designates generally the frame of the machine which is composed of heavy material and strengthened by cross pieces 1 and the braces 2. The braces 2 are angularly disposed and cross each other at the longitudinal center line of the frame A. The frame A is of considerable length and is supported by six sets or pairs of wheels 3, the front wheels 3' being swiveled to the front of the frame as shown at 4 in Figure 4 of the drawings.

A shaft 5 is journaled in the frame an appreciable distance from the center thereof and to the rear of the frame and this shaft is formed with crank ends 6 which are located beyond the sides of the frame, the extremities of the cranks forming journals for the large wheels 7. Thus by partly rotating the shaft in one direction the wheels 7 will be lowered to engage the ground or road surface and thus lift the frame A so that all the wheels 3 will be lifted off the ground with the exception of the front wheels 3'. When the shaft is partly rotated in an opposite direction the wheels 7 will be lifted so that the wheels 3 will contact the road surface. A lever 8 is connected with the shaft 5 and a cable 9 extends from the upper end of the lever to a drum 10 journaled in the front of the frame A and the axle of said drum is connected by the gears 11 to a shaft 12 which is provided with a hand wheel 13 arranged at a point where the operator can readily reach the same for manipulation thereof.

The scraper blade 14 is adjustably connected in any suitable manner to the holder 15 which is raised and lowered by the screw shafts 16 having the hand wheels 17 connected to their upper ends. Each of the screw shafts 16 is mounted in a bearing member 18 disposed crosswise of the frame A and the said shaft carries jamb nuts 19 which contact with the bearing 18 on adjustment for taking out all vertical play to the blade 14 by locking the rotation of the screw shaft 16.

The blade carrier slidably fits within cast-

ings 20 arranged on the side sills of the frame A and these castings are designed to hold the carrier in vertical position and to permit free movement when adjusting up or down.

5 Formed on the carrier adjacent to the connection of each shaft 16 therewith is an ear 21 to which is pivoted at 22 a swinging arm 23, the same being pivoted at 24 to a thrust casting 25 and this arm acts to shove blade 14 ahead instead of pulling upon the same and by such mounting of the carrier it eliminates vibration of blade and throws the weight of the machine onto the blade at all times when cutting.

10 15 When the blade is properly adjusted it will not be necessary to change the same for a long time as the construction of the machine enables the blade to do its work without the help of a man to adjust the same.

20 The length of the machine is quite an asset and makes it possible for the machine to do excellent work, as by making the machine of considerable length and supporting it by the six sets or pairs of wheels, the blade 14 is held out of low places and is not permitted to go too deep in high places. By using a plurality of wheels the machine is kept out of holes and at the same time the blade is prevented from cutting too deep. By making the machine of considerable weight the blade will cut the road surface regardless of small obstacles and the roughness of the road and the blade will cut smoothly and only where needed. By lowering the wheels 25 30 35 40 45 50 55 60 65 70 75 80 85 90 95 100 105 110 115 120 125 130

At the front end of the frame A is arranged a quadrant 26, the ends of which are horizontally pivoted at 27 so that said quadrant will have free vertical movement while mounted centrally of the forward end of the frame A is a coupling 28 for a laterally swinging tongue 29, this being the draft tongue and being susceptible of lateral angular adjustment upon the quadrant 26, the latter being formed with spaced holes 30 and likewise the tongue has a hole 31 for registration with the holes 30 and these last adjustably accommodate a pin 32 so that the tongue 29 can be fastened in its adjusted position. The quadrant 26 near opposite ends is formed with stops 33 which limit the lateral swinging of the tongue. The tongue 29 is swung against either of the stops 33 when it is desired to make a sharp turn either right or left.

60 The forward corner portion of the frame A has fitted therein tension rods 34 which serve to transfer pull of tractor of the frame of the machine, these rods being disposed in a forwardly convergent relation to each other 65 and being fitted within the front end of the

frame close to opposite sides of the coupling 28.

It is thought from the foregoing description that the advantages and novel features of the invention will be readily apparent. 70

It is to be understood that changes may be made in the construction and in the combination and arrangement of the several parts, provided that such changes fall within the scope of the appended claims. 75

What is claimed is:—

1. A road grading machine comprising a frame of considerable weight and length, a plurality of pairs of wheels for supporting the frame, means for swivelling the front wheels to the frame, a blade carried by the frame, a pair of extra wheels located rearwardly of the central part of the frame, and means for raising and lowering the said wheels, said extra pair of wheels, when lowered, lifting the frame with all but the front pair of wheels off the ground. 80

2. A road grading machine comprising a frame, a plurality of pairs of wheels for supporting the frame, means for swiveling the front wheels to the frame, a blade carried by the frame, a pair of extra wheels located rearwardly of the central part of the frame, said extra pair of wheels when lowered lifting the frame with all but the front pair of wheels off the ground, a shaft journaled in the frame and having crank ends to which the extra pair of wheels is connected, and means for rocking the shaft from the front end of the machine. 90

3. A road grading machine comprising a frame of considerable weight and length, a plurality of pairs of wheels for supporting the frame, means for swivelling the front wheels to the frame, a blade carried by the frame, a pair of extra wheels located rearwardly of the central part of the frame, means for raising and lowering the said wheels, said extra pair of wheels, when lowered, lifting the frame with all but the front pair of wheels off the ground, a blade carrier fitted within the frame for vertical sliding movement, and arms pivoted in the frame and to the carrier to exert a forward thrust to the blade carrier. 100

In testimony whereof I affix my signature.
THOMAS P. WRIGHT.
